UNITED STATES PATENT OFFICE.

ROBERT W. YOUNG, OF WILMETTE, ILLINOIS.

TURNTABLE-DRIVING APPARATUS.

Application filed August 20, 1926. Serial No. 130,393.

The invention disclosed herein relates to railway turntable construction and more particularly to a type of construction adapted for use in turntables receiving heavy loadings. While the invention is peculiarly adapted for a three-point or unbalanced center bearing turntable construction, it will be obvious that it is applicable to other types of turntables, such as the single span type without center or to the center balanced type for converting the latter to a three-point bearing type.

Railway rolling stock has been and is ever increasing in weight and this fact has made it increasingly difficult to utilize the center bearing balanced type. The continuous three-point bearing type and the single span type without center are therefore coming more and more into general use. Regardless of the type of turntable it is desirable that it be so mounted on the trucks or, in other words, so connected to the trucks that the trucks may swing, pivot or give to some extent with respect to the girders so as to maintain the wheels of the truck, whether driven or simple idling wheels, in contact with the turntable track or rail at all times. It is well known that the average pit rail or track of a turntable is uneven and whether the turntable be of the center balanced type or not, if its truck be secured rigidly or inflexibly thereto, the strain upon the center bearing, girders and other vital structural parts of the turntable is tremendous when heavy rolling stock passes thereon and the truck wheels are not directly supporting the ends of the girders from the pit rail. In other words, should there be a depression in the pit rail beneath the girder having a rigidly connected truck, the girder will not be supported from the rail when heavy rolling stock passes on to the table and great bending and torsional stresses are placed upon the girders and other portions of the table tending to strain them.

Another undesirable feature of such construction is encountered when the truck wheels fail to contact with the track due to unevenness therein, if such truck wheels are the driving means by which the turntable is rotated, for in this case, unless the girders flex sufficiently to contact the driving wheel with the circle or pit rail, no traction whatsoever can be secured.

One of the primary objects of my invention is to provide a truck construction appli-

cable to both simple and driven trucks and to provide each truck with an equalizer, such as a pivot or hinge connection to the turntable girder in order that the wheels of the truck may adjust themselves to uneven portions of the circle or pit rail, thus furnishing constant traction without putting excess strain on the table girders or excess load on the motors, which is the case when the trucks are rigidly attached to the girders. Turntable trucks have been somewhat flexibly connected to turntables before but my invention provides a flexible connection which is in fact flexible and cannot impose torsional or other strains on the table members with which it is connected. My invention attains these ends and also greatly simplifies turntable construction in that I pivot the truck to the girder on an axis parallel to the plane of the girder and preferably in the plane of the girder.

Another object is to provide a truck construction which may be applied to any turntable girder end, whether the turntable be previously installed or not, and one which may either be connected to the turntable girder directly beneath it for a deep pit, or in a notch formed in the end thereof for shallow pits, or through an opening formed through the web of the girder adjacent the end over the pit track in the same or other instances.

Still another object is to provide a truck arrangement adapted to be constructed either as a simple truck or a driven truck and to arrange the driving mechanism on the truck, in case it is a driven truck, in such a position and relation to other parts of the truck and turntable as to most efficiently and effectively economize space and at the same time utilize the weight of the driving means including the prime mover, to maintain the driving wheel of the truck in contact with the pit rail at all times and regardless of inequalities therein.

A further object is to provide a simple and efficient pivot or hinge connection between the girder and the truck of such character that substantially one size of hinge connection may be utilized to obtain various depths of connection between the girder and truck to adapt a truck to various turntable girders regardless of their height above the pit rail.

A still further object of the invention is to provide a frame and journal construction of such character that the same frame may be utilized with the same or different journals for turntables of different radii. For this pur-

pose a suitable seat and positioning means are provided on the frame of the truck, while the portions of the journals adapted to engage the positioning means and to connect the journals to the frame are so constructed that they may be machined to cooperate with the seat and positioning means on the frame to dispose the axes of the journals of the trucks on or substantially parallel to the radius of the particular table being constructed or equipped.

Further objects including improved structural arrangements and combinations of parts, as well as the advantages of my invention, will be or should become readily appreciated after perusal of the following description and claims taken in connection with the drawings in which:

Fig. 1 is a top plan view of a portion of one end of a turntable showing a simple and a power driven truck connected thereto through the ends of the girders.

Fig. 2 is an end elevation of the construction illustrated in Fig. 1 looking radially inward of the turntable.

Fig. 3 is a top plan view of a power driven truck, taken on the line 3—3 of Fig. 4.

Fig. 4 is a rear elevational view of the power driven truck, taken on the line 4—4 of Fig. 3.

Fig. 5 is a vertical sectional view through the journals and journaled to frame connecting members, taken on the line 5—5 of Fig. 3 and showing the driving wheel and its axle mounted therein.

Fig. 6 is a sectional view through a preferred type of hinge for connecting the truck frame to the girder, taken on the line 6—6 of Fig. 4.

Fig. 7 is a top plan view of the idling wheel, its axle and journal-to-frame connecting members showing a portion of the truck frame in section, taken on the line 7—7 of Fig. 4, and

Fig. 8 is an end elevation of one of the hinge members or elements for pivotally connecting the truck frame to a girder.

The girders illustrated are of the so-called built-up type and may include one or more web plates 2 (in the present instance three are shown) which are secured together in any suitable manner. Angle irons 3, preferably extending the full length of the webs, are connected thereto at their tops and bottoms, as is well understood. The bridge-type girders illustrated have webs of greater height over the center portions of the table than at their ends, the top being tapered down from a point a suitable distance on either side of their centers to their ends adjacent the pit wall. The girders are, of course, suitably interbraced and connected by members 5, 6, 7 and 8 in any desired or preferred manner and the turntable frame structure thus formed may or may not, according to its type, be

mounted upon a center bearing for manual or mechanical rotation within the turntable pit, the rim of which is indicated at 9. In practically all turntables of the power driven type a single circle or pit rail 10 is provided adjacent the walls of the pit and adapted to serve either as a support for the table end, or as a traction surface for the driving wheel of a truck or tractor for rotating the turntable, or both as a support for the turntable end and a traction surface for the driving wheel or wheels.

In the arrangement shown for simple illustration of my invention I have depicted a turntable having both simple and driven trucks at one end; the simple truck, generally designated 11, being located at the left of Figs. 1 and 2 and the driven truck, generally designated 12, at the right, although it will be understood that both trucks may be simple trucks or even both driven trucks, if for any reason such is desirable. While, as has been intimated above, the trucks may be connected to the girders in notches cut in the ends thereof or in any other desirable manner, I prefer to cut an opening designated 13 through the web of the girder adjacent its end and between the top and bottom sides thereof through which one end of the truck frame is disposed.

While in the construction illustrated, the top of the girder converges toward the bottom at the ends of the girder, the construction is such that the web of the girder may be cut out to provide an opening of sufficient size over or adjacent the circle or pit rail to receive the truck frame and its pivot member therethrough without materially decreasing its strength. It will be understood, of course, that the girders will be constructed of sufficient strength to permit this being done. While all of the edges of the rectangular opening 13 through the girder web may be reinforced with angle irons or other structural elements, I prefer to reinforce only the top edge. For this purpose I utilize angle irons 14 which also serve to secure one portion of the hinge or pivot member of the truck to the girder, as will be seen.

Referring now more particularly to Figs. 3 and 4, the frame of the truck is generally designated 15 and is of such length that it may extend on opposite sides of the girder to support an idling wheel 16 on one side and a driven wheel 17 on the other. The frame member 15 is preferably a steel casting, the sides of which are adapted to extend substantially perpendicular to the plane of the girder for a short distance on either side of its pivotal connection thereto when in position. From this portion the frame extends obliquely away from the girder in order that the wheels, whether driven or idling, may be positioned properly with respect to the turntable track or rail 10. For the driven trucks,

the end of the frame extending away from or on the outside of the turntable is made longer than the end extending inwardly in order to provide room properly to support the prime mover and other driving mechanism, while for simple trucks the frame preferably extends equally on each side of the girder to which it is attached.

The frame is pivotally attached to the girder on an axis parallel to and adjacent or parallel to and lying in the plane of the web of the girder and for this purpose an upper hinge member comprising a plate 18 having a series of depending arms 19 (see Fig. 6), each drilled to receive a hinge pin 21, is secured to the angle members 14 attached to the web of the girder by means of bolts 22 and nuts 23 which are passed through bolt holes 20 drilled through the plate 18 and registering holes (not shown) in the angles 14. Shims 24 may be interposed between the plate 18 and the bottoms of the angle members 14 for adjustment, if desired, but the primary adjustment of the hinge and thus the truck 25 is secured through the depending arms 19, as will be hereinafter described. The frame 15 at the place where it is to be hinged to the girder is provided with a series of integral webs 25, each having a head 26 adapted to fit between the arms 19 and to be drilled in the same manner as the arms 19 to receive the hinge pin 21. The arms 19 are preferably of such length that they may be drilled on any one of a plurality of centers, as indicated in dotted lines in Fig. 8, to secure a primary adjustment for various heights of the girder openings above the turntable track or circle rail. In other words the frame may be pivotally connected to the plate and thus to the girder at various vertical distances therefrom. If further adjustment is needed it is secured by the use of shims 24, as will be understood.

The hinge or pivot pins 21 are preferably secured to the frame member and I prefer to accomplish this by drilling and tapping a hole located partially in the pin and partially in one of the heads 26 for the reception of a screw key 27, as shown in Fig. 4, but this end may be attained in other ways. Since the pin is secured against rotation relative to the frame of the truck it is only necessary to lubricate its points of bearing in the arms of the upper hinge member 18. I have shown one conventional method of accomplishing this purpose in Fig. 6 wherein the pin 21 is shown in dotted lines as drilled axially, as at 28, and radially, as at 29, to provide oil or grease ducts. An opening for supplying the ducts with lubricant is provided in one end of the pin and adapted to be normally closed by a plug 31, but other means of lubricating this hinge or pivot pin may be provided, as will be understood.

The wheels of the simple trucks are prefer-

ably mounted in substantially the same manner as the idling wheel 16 of a driven truck and for that reason a description of the latter should suffice for all. The frame at both ends is recessed on the bottom side, as shown 70 at 32 and 33, to provide clearance for the idling and driving wheels 16 and 17, respectively, and is also preferably recessed, as at 34 and 35, for lightness and to adapt the frame to be dropped away from the girder 75 when attached in an undercut slot, notch or recess in the girder end, or from the hinge member or element 18 after the hinge pin 21 and the wheels and their axles have been removed, if for purpose of repair or otherwise 80 this should be desirable.

The recess 34 provides spaced arms 36 and 37, the bottoms of which are planed off to provide seats 38 for the journal attaching or supporting members 39 and 41 respectively. 85 Adjacent each seat 38 aligned shoulders 42 are provided on the frame and preferably extend substantially transversely of the arms 36 and 37 to abut and position the journal members 39 and 41 through their edges 43 90 which are machined to lie in alignment with one another. The shoulders 42 preferably occupy the same directional relationship to all frames regardless of the radius length of the turntable to which the frames are applied, but since it is desirable to have the axes of the axles of the wheels and therefore the axes of the journal boxes, whether for simple or driven trucks, lie parallel to a radius 95 of the turntable, the edges or shoulders 43 100 of the journal connecting or supporting members are milled off at such angular relation with respect to the axis of the journals or axles as will dispose the axis of the journal or axle parallel a radius of the particular 105 turntable to which the journal supporting members are applied when the shoulders 43 abut the shoulders 42. The journal supporting members are connected to the frame by means of bolts 44, although they may be connected otherwise, as desired.

In Fig. 5 I have shown in cross section a preferred arrangement and construction for the driving wheel mounting. As shown the driving wheel 17 is keyed or otherwise secured on its axle 45 which is reduced, as at 46 and 47, for mounting in journal boxes 48 and 49 respectively, and extended and further reduced, as at 51, for the reception of a gear 52 which is keyed thereon. The journal boxes 48 and 49 are of similar construction, each embodying cupped members 53 within which roller bearings 54 are mounted in their races and closure caps 55 and 56 respectively. The cap 55 serves both as a closure for the bearing and as a thrust member for the axle 46, while the closure member 56 is of slightly different construction in that it is provided with an opening through which the extension end of the axle projects and 120 125 130

has a thrust washer 57 abutting between the inner face of the member 56 and the shoulder formed by the reduced portion 51 of the axle serving to absorb the thrust imparted to the 5 axle to the right in Fig. 5. Each of the closure members 55 and 56 is secured to its respective cup member 53 by means of bolts 58 and 59, while the cast steel frame member, by reason of the recess 35, forms arms 61 and 10 62 which are secured to the journal members through bolts 63 in substantially the same manner as the journal members 41 are connected to the frame arms 36 and 37. The frame arms 61 and 62 are also provided with 15 shoulders 64 cooperative with the journals 48 and 49 in the same manner and for the same purpose as the shoulders 42 cooperate with the shoulders 43.

The driving mechanism for the driving 20 wheel 17 preferably comprises a suitable electric motor 65 mounted on legs 66 secured by bolts 67 to the flanged sides to the top of the frame, a gear 68 carried by the shaft of the motor for driving engagement with a large 25 reducing gear 69 mounted in journals 72 secured on the arms 61 and 62 of the frame 15, and a gear 73 secured on the opposite end of shaft 71 for driving engagement with gear 52 secured on the end 51 of shaft 45. The 30 motor 65, as will be noted, is mounted between a vertical projection of the axis of shaft 45 and the plane of the web of the girder, since this arrangement, from engineering and commercial standpoints, has been found to be 35 most efficiently effective and satisfactory.

The motor controller may be suitably arranged from any cab mounted on the turntable or from other places of remote control and per se forms no part of the present invention. The power mechanism is preferably equipped with a braking mechanism of any suitable character. For the purpose of illustration I have shown a brake drum 74 secured on shaft 71 for engagement by brake shoes 75 40 carried by yoke arms 76 and 77 pivoted together at 78 at their bottom ends and connected by an adjustable bolt member 79 adjacent their upper ends. A toggle mechanism partially indicated at 81 is connected through 45 suitable links or rods with a brake lever or pedal in the operator's cab, as will be understood.

It is believed that from the foregoing description and statement the preferred construction and arrangement of parts of my invention, as well as the advantages and novelties thereof, will be appreciated, but as radical departure from the specific arrangement and form of the embodiment of the invention, shown and described for illustrative purposes only, may be made without departing from the purview of the invention, I desire to be limited only by the spirit thereof and the scope of the appended claims.

65 I claim:

1. In a turntable, a pit-rail, a girder having a recess formed therein adjacent the pit rail, a member extending through said recess, a single pivot having an axis parallel to the plane of the girder for securing said member to said girder for swinging movement with respect thereto, said member being otherwise unconnected to said girder, and a wheel mounted on said member for rolling on said pit rail. 70

2. In a turntable, a girder, a truck frame member, a horizontal pivot connection the axis of which is parallel to the plane of the girder between said member and girder, said member and girder being otherwise unconnected, and a truck wheel rotatably supported 80 by said member.

3. In a turntable, a girder, a truck frame member extending transversely of said girder and pivoted thereto between its ends on an axis parallel to the plane of the girder, said member and girder being otherwise unconnected, and a truck wheel rotatably mounted 85 on said member on each side of said girder.

4. In a turntable, a girder, a truck frame member extending transversely of said girder and pivoted thereto between its ends on an axis parallel to the plane of the girder, said member and girder being otherwise unconnected, and a truck wheel rotatably mounted 90 on said member on each side of said girder, the axes of said wheels lying substantially along radii of the turntable. 95

5. In a turntable, a girder, a truck frame member extending transversely of said girder and pivoted thereto between its ends on an axis parallel to the plane of the girder, said member and girder being otherwise unconnected, a truck wheel rotatably mounted on 100 said member on each side of said girder, and driving means for rotating one of said wheels. 105

6. In a turntable, a girder, a truck frame member extending transversely of said girder and pivoted thereto between its ends on an axis parallel to the plane of the girder, said member and girder being otherwise unconnected, a truck wheel rotatably mounted on 110 said member on each side of said girder, and driving means for rotating one of said wheels, the axes of said wheels lying substantially 115 along radii of the turntable.

7. In a turntable, a girder adapted to extend across a turntable pit substantially parallel to a radius of the pit, said girder having a recess in one end, and a truck member disposed through said recess and connected to 120 said girder solely by a single pivot member.

8. In a turntable, a girder adapted to extend across a turntable pit substantially parallel to a radius of the pit, said girder having a recess in one end, and a truck member disposed through said recess and connected to 125 said girder solely by a hinge.

9. In a turntable, a girder adapted to extend substantially parallel with a radius of 130

- a turntable pit, a truck member extending substantially transversely of and across said girder, and a relatively free swinging hinge connecting said member to said girder.
- 5 10. In combination with a turntable supporting girder having one end adapted to extend adjacent a pit rail, means connected by a pin and eye hinge to said girder adjacent said end for relative and substantially free swinging movement with respect thereto about an axis parallel with the plane of said girder, and a wheel rotatably carried by said means for running on the pit rail.
- 15 11. In combination with a turntable supporting girder having one end adapted to extend adjacent a pit track, means connected by a pin and eye hinge to said girder adjacent said end for relative and substantially free swinging movement with respect thereto about an axis parallel with the plane of said girder, and a wheel rotatably carried by said means on an axis substantially radial of the turntable pit for running on the pit rail.
- 20 12. In combination with a turntable supporting girder having one end adapted to extend adjacent a pit track, a truck frame member, and a hinge pivotally connecting said member to said girder at said end on an axis oblique to a radius of the turntable intersecting said girder at said end, for supporting the girder from said pit track, said hinge forming the sole connection between said member and girder.
- 25 13. In combination, a turntable pit having a pit rail, a turntable including a girder within said pit and extending thereacross, the ends of the girder extending into proximity to said rail, a truck member pivotally connected to one end of said girder on an axis oblique to a radius of said pit rail for relatively extreme and unlimited tilting movements relative to said girder, and a truck wheel rotatably secured to said member for supporting the same from said pit rail.
- 30 14. In a turntable, a girder end adapted to extend adjacent a pit rail, and a support for said end comprising a wheeled truck having a single non-distorting and flexible connection to said girder, disposed beneath a portion of said girder end, said truck being otherwise unconnected to said girder.
- 35 15. In a turntable, a girder and a support for said girder comprising a truck member having a single connection to the girder, said connection being flexible without distortion, said truck member being otherwise unconnected to said girder.
- 40 16. In a turntable of the continuous girder type, a pair of girders suitably interconnected, and extending on either side of a diameter of the turntable, a supporting truck for each of the ends of one of said girders, and a single connection between each truck
- 45 and the adjacent girder end, said connection being flexible without distortion.
- 50 17. In a turntable construction, a truck frame member, a bearing member connected to said frame member adjacent one end thereof, a wheel journalled in said bearing member with its axis of rotation transverse to the length of the frame member, and a hinge element having an opening for reception of a hinge pin, connected to said frame member between the axis of the wheel and the opposite end of said frame member.
- 55 18. A truck for supporting an end of a turntable girder comprising, a frame member adapted to be disposed substantially transverse to the plane of the girder, a wheel rotatably connected to said member adjacent one thereof for running on a pit rail, and means providing a hinge for connecting said member to the girder for swinging movements with respect thereto on a horizontal axis parallel to the plane of the girder.
- 60 19. In combination with a turntable supporting girder having an end adapted to extend into proximity to a table pit rail, a truck member connected to and extending transversely across the end of said girder for supporting the same, a pair of driving wheels for supporting and driving said truck from said rail, said wheels being disposed on opposite sides of said girder and a prime mover disposed intermediate one of said wheels and girder and operatively connected to one of said wheels for driving the same.
- 65 20. In combination with a turntable supporting girder having one end adapted to extend adjacent a pit track, a wheel carrying member disposed transversely of and connected intermediate its ends to the said end of said girder, a driving wheel carried by said member adjacent one end thereof for running on the pit track, and a prime mover carried by said member intermediate the axis of said wheel and the connection of said member to said girder for driving said wheel.
- 70 21. In combination with a turntable supporting girder having one end adapted to extend adjacent a pit track, a wheel carrying member disposed transversely of and connected intermediate its ends to the said end of said girder, a driving wheel carried by said member adjacent one end thereof for running on the pit track, a prime mover carried by said member intermediate the axis of said wheel and the connection of said member to said girder for driving said wheel, and gearing supported by said member between the axis of said wheel and the adjacent end of said member for connecting said prime mover and wheel.
- 75 22. In combination with a turntable supporting girder having one end adapted to extend adjacent a pit track, a wheel supporting member disposed transversely of and con-

- 5 nected intermediate its ends to the said end of said girder, a driving wheel rotatably supported by said member adjacent one end thereof and adapted to run on the pit track, a prime mover disposed between the last said end of said member and said girder for driving said wheel, and a pivot connection between said member and said girder.
- 10 23. In combination with a turntable supporting girder having one end adapted to extend adjacent a pit track, a wheel carrying member disposed transversely of and connected intermediate its ends to the said end of said girder, a driving wheel carried by said member adjacent one end thereof for running on the pit track, a prime mover carried by said member intermediate the axis of said wheel and the connection of said member to said girder for driving said wheel, and a pivot connection between said member and said girder.
- 15 24. In combination with a turntable supporting girder having one end adapted to extend adjacent a pit track, a wheel carrying member disposed transversely of and connected intermediate its ends to the said end of said girder, a driving wheel carried by said member adjacent one end thereof for running on the pit track, a prime mover carried by said member intermediate the axis of said wheel and the connection of said member to said girder for driving said wheel, gearing supported by said member between the axis of said wheel and the adjacent end of said member for connecting said prime mover and wheel, and a pivot connection between said member and said girder.
- 20 25. In combination with a turntable supporting girder having one end adapted to extend adjacent a pit track, a wheel supporting member disposed transversely of and connected to the said end of said girder, a driving wheel rotatably supported by said member adjacent one end thereof and adapted to run on the pit track, a second wheel rotatably supported by said member in spaced relation to said driving wheel, and a prime mover disposed between the last said end of said member and said girder and between said wheels for driving said driving wheel.
- 25 26. In combination with a turntable supporting girder having one end adapted to extend adjacent a pit track, a wheel carrying member disposed transversely of and connected to the said end of said girder, a driving wheel carried by said member adjacent one end thereof and at one side of said girder for running on the pit track, a second wheel mounted on said member on the opposite side of said girder, and a prime mover carried by said member intermediate the axis of said driving wheel and the connection of said member to said girder and between said
- 30 wheels on the arc of said track for driving said wheel.
- 35 27. In a device as set forth in claim 26 the combination of gearing supported by said member between the axis of said driving wheel and the adjacent end of said member for connecting said prime mover and driving wheel.
- 40 28. In combination with a turntable supporting girder having one end adapted to extend adjacent a pit track, a wheel supporting member disposed transversely of and connected to the said end of said girder, a driving wheel rotatably supported by said member adjacent one end thereof and adapted to run on the pit track, a prime mover disposed between the last said end of said member and said girder for driving said wheel, and a pivot connection between said member and said girder.
- 45 29. In combination with a turntable supporting girder having one end adapted to extend adjacent a pit track, a wheel carrying member disposed transversely of and connected to the said end of said girder, a driving wheel carried by said member adjacent one end thereof for running on the pit track, a prime mover carried by said member intermediate the axis of said wheel and the connection of said member to said girder for driving said wheel, and a pivot connection between said member and said girder.
- 50 30. In combination with a turntable supporting girder having one end adapted to extend adjacent a pit track, a wheel carrying member disposed transversely of and connected to the said end of said girder, a driving wheel carried by said member adjacent one end thereof for running on the pit track, a prime mover carried by said member intermediate the axis of said wheel and the connection of said member to said girder for driving said wheel, gearing supported by said member between the axis of said wheel and the adjacent end of said member for connecting said prime mover and wheel, and a pivot connection between said member and said girder.
- 55 31. In a turntable construction of the character described, a hinge element having a projection of sufficient length to be provided with any one of a series of transverse openings for the reception of a hinge pin therethrough, and means for securing said element to one of two relatively swinging devices.
- 60 32. In combination with a turntable girder member and a truck member, a hinge element forming part of a hinge for connecting the truck to the girder comprising, means for securing said element to one of said members and means of sufficient area to have any one of a series of openings provided therethrough for reception of a hinge pin at a selected distance from said securing means.
- 65 33. In combination with a structural ele-

- ment of a turntable, means for pivotally connecting a truck thereto comprising a hinge element having an arm portion, said portion being of an area sufficient to adapt it to be provided with a hinge pin receiving recess at any one of a plurality of locations over said area.
34. In combination with a first structural element of a turntable, means for pivotally connecting a second structural element there-
- 10 to comprising a hinge member having a substantially flat base adapted to be removably secured to the first structural element, and a pair of substantially parallel spaced arms projecting transversely from said base in the
- 15 same direction.
35. In combination with a first structural element of a turntable, means for pivotally connecting a second structural element there-
- 20 to comprising a hinge member having a base adapted to be secured to the first structural element, and a pair of substantially parallel spaced arms projecting from said base in the same direction, said arms each being of sufficient area in the the planes of their parallelism to adapt each of them to be provided with a hinge pin receiving recess at any one of a plurality of places over its said area.
36. In a turntable, a girder end adapted to extend adjacent a pit rail and having an
- 30 opening therethrough spaced from said end and intermediate the top and bottom of the girder, and a truck frame member disposed through said openings and pivotally connected to said girder adjacent said opening,
- 35 said frame member being otherwise unconnected to said girder.
37. In a turntable truck, a frame member having a portion adapted to be disposed substantially tangentially of a circle concentric
- 40 with the center of the turntable, and a seat on said frame member having a shoulder adapted to abut against a portion of and position a journal member for a wheel axle so that the axis of the axle will be disposed
- 45 radially of said turntable center.
38. In a turntable truck, a frame member having a portion forming a journal connecting member seat, and a rib projecting adjacent said seat, said rib having a planed surface providing an abutment for a portion of each of a plurality of journal connecting members adapted to be attached to said seat to align the axis of each journal with a radius of a turntable.
- 55 39. In a turntable truck, a frame adapted detachably to engage a pair of axially aligned wheel axle journal supporting members carrying journals, and means for aligning the axes of said journals with a radius of the turn-
- 60 table including a projection on said frame providing a shoulder adapted to engage a corresponding shoulder on one of said supporting members.
40. In combination with a structure as defined in claim 39, said projection being adapted to position a plurality of journal supporting members each having a shoulder adapted to engage the said shoulder on the frame for interchanging the journal supporting members for turntable tracks of different radii.
41. In a turntable truck, a frame member and means for connecting corresponding wheel axle journals to said frame to have their axes parallel to turntable radii of various lengths comprising, a seat on said frame member against which said supporting member may be secured, a shoulder extending at a fixed angle with respect to a turntable radius adjacent said seat, and journal supporting members each having a portion adapted to be machined to such angle with respect to the axis of its journal as to provide a shoulder cooperative with the shoulder on said frame member to dispose the axis of its corresponding journal parallel with a turntable of predetermined radius.
42. In a turntable driving truck, a unitary frame comprising a substantially central portion adapted to be disposed parallel to a tangent to the turntable circumference, integral end portions connected to and extending obliquely away from said central portion, each end portion lying substantially parallel to other tangents to the turntable circumference, and a plurality of parallel hinge elements secured to said central portion.
43. In a turntable driving truck, a frame comprising a substantially central portion adapted to be connected to a turntable girder and to be disposed substantially parallel to a tangent to the turntable circumference, end portions connected to and extending obliquely away in opposite directions from said central portion, and means for connecting said portions to the turntable girder comprising a plurality of parallel webs on said central portion, said webs lying in vertical planes substantially parallel to the first said tangent.
44. In a turntable driving truck, a frame comprising a substantially central portion adapted to be connected to a turntable girder and to be disposed substantially parallel to a tangent to the turntable circumference at its connection to the girder, end portions connected to and extending obliquely away in opposite directions from said central portion and each disposed substantially parallel to other tangents to the turntable circumference, and means for pivotally securing said frame to a turntable girder.

In witness of the foregoing I affix my signature.

ROBERT W. YOUNG.
